Primary Examiner — Sanjeev Paul(74) *Attorney, Agent, or Firm* — Cantor Colburn LLP(57) **CLAIM**

I claim, the ornamental design for glasses, as shown and described.

DESCRIPTION

FIG. 1 is a perspective view of glasses, showing my new design;

FIG. 2 is a front elevational view thereof;

FIG. 3 is a rear elevational view thereof;

FIG. 4 is a left side elevational view thereof;

FIG. 5 is a top side elevational view thereof;

FIG. 6 is a bottom plan view thereof;

FIG. 7 is an enlarged detail view of the glasses shown in FIG. 1; and,

FIG. 8 is a right side elevational view.

The broken lines shown in the drawings are included for the purposes of illustrating unclaimed portions of the glasses and form no part of the claimed design.

1 Claim, 8 Drawing Sheets(56)
